 tion of Indiana

Application April 6, 1937, Serial No. 135,291

23 Claims. (Cl. 15—50)

My invention relates to scrubbing machines for cleaning floors, decks, platforms, and similar locations having an extended area, and is principally concerned with providing a self-propelled machine for scrubbing, rinsing, collecting the dirty water and wiping the floor along a strip of predetermined width.

One object of my invention is to devise a machine of the character indicated in which the brushes apply a substantially constant scrubbing pressure by being adapted to freely and individually position themselves in response to irregularities and malformations in the floor and further in which the brushes are so related that the space covered thereby is cleaned without streakiness.

A further object is to provide a scrubbing machine in which the quantity of water and cleaning compound or soap powder delivered to each brush can be accurately controlled to insure an economical use of these materials and an equal consumption thereof by each brush, as well as the preparation of a cleaning emulsion of proper strength, or mixture.

A further object is to provide for the premixing of the water and compound in advance of the delivery of these materials to the brushes, the water being directed to prevent any clogging by the compound of the supply line leading to each brush.

A further object is to provide a scrubbing machine in which water is delivered to the brushes for scrubbing and also directly on the floor rearwardly of the brushes as the machine is advanced in order to further liquify the emulsion of water and dirt left by the brushes and so facilitate its removal.

A further object is to devise a machine as noted above in which provision is made for collecting the dirty water and withdrawing the same from the floor into a suitable receptacle, the collecting device additionally operating to wipe the floor clean.

A further object is to provide a scrubbing machine equipped with a mop or squeegee device and with vacuum mechanism for lifting the dirty water from the floor into a storage receptacle on the machine, the operation of the vacuum device being controlled by the movement of the squeegee to working position.

A further object is to devise a self-propelled scrubbing machine in which the connections between the power source and the driving wheels are arranged to provide for a free movement of one of the wheels while maintaining a driving

connection to the other wheel when the direction of the machine is changed, thus enabling the machine to turn corners easily.

These and further objects of my invention will be set forth in the following specification, reference being had to the accompanying drawings, and the novel means by which said objects are effectuated will be definitely pointed out in the claims.

10 In the drawings:

Fig. 1 is a side elevation of my improved machine showing the scrubbing and squeegee mechanisms in operative relation to the floor, the controlling devices for these mechanisms, and the powder distributor.

Fig. 2 is a plan view of the switch box and voltage regulator which control the operation of the several motors mounted on the machine, as viewed in the direction of the arrow 2 in Fig. 1.

Fig. 3 is a view similar to Fig. 1, but looking at the opposite side of the machine.

Fig. 4 is an enlarged side elevation of the machine, as viewed in Fig. 1, certain protective shields being removed to expose the drive constructions for the scrubbing mechanisms, the piping for controlling the water distribution for scrubbing and rinsing, and the distributor which regulates the flow of cleaning compound to the brushes.

Fig. 5 is a plan view of the machine chassis or frame, the clean and dirty water tanks being removed.

Fig. 6 is an enlarged section taken along the line 6—6 in Fig. 5, looking in the direction of the arrows, and showing the construction for transmitting power to the driving wheels of the machine.

Fig. 7 is a section along the line 7—7 in Fig. 6, looking in the direction of the arrows.

Fig. 8 is an enlarged, sectional view of the clutch which controls the transmission of power between the main driving motor and the driving wheels of the machine.

Fig. 9 is a section along the line 9—9 in Fig. 8, looking in the direction of the arrows.

Fig. 10 is a vertical, sectional elevation of the right-hand driving wheel, as viewed in the direction of the arrow 10 in Fig. 3.

Fig. 11 is a fragmentary elevation of one of the shoes which establish a driving connection between the driving axle and the driving wheels.

Fig. 12 is an enlarged, front elevation of the lower portion of the machine, as viewed in the direction of the arrow 12 in Fig. 3, showing the

scrubbing mechanism and the powder distribution to each mechanism.

Fig. 13 is an enlarged, side elevation of the lower portion of the machine, looking in the direction of the arrow 13 in Fig. 12.

Fig. 14 is a view of the underside of the scrubbing mechanism, looking in the direction of the arrow 14 in Fig. 13.

Fig. 15 is an enlarged elevation, partly in section, of the left-hand scrubbing mechanism, as viewed in Fig. 12, showing the universal mounting of each brush, the brush being rotated through an angle of 90° from the position illustrated in Fig. 12.

Fig. 16 is an enlarged, sectional elevation taken along the line 16—16 in Fig. 5, looking in the direction of the arrows, and showing the arrangement of the piping for distributing water to the brushes for scrubbing and to the floor for rinsing.

Fig. 17 is an enlarged, fragmentary elevation, looking in the direction of the arrow 17 in Fig. 16, and showing the adjusting arrangement for securing an equal rate of water flow to each brush.

Fig. 18 is an end elevation of the adjusting arrangement shown in Fig. 17, looking in the direction of the arrow 18 in said figure.

Fig. 19 is an enlarged side elevation of the operating handle and associated parts for controlling the water flow to the brushes, as viewed in Fig. 1.

Fig. 20 is a section along the line 20—20 in Fig. 19, looking in the direction of the arrow.

Fig. 21 is an end elevation, partly in section, of the powder distributor as viewed in Fig. 3, and showing the driving mechanism for the agitators in the powder container and the powder conduits.

Fig. 22 is a sectional elevation of the distributor taken along the line 22—22 in Fig. 23, looking in the direction of the arrows, and showing the container and conduit agitators.

Fig. 23 is a section along the line 23—23 in Fig. 21, looking in the direction of the arrows.

Fig. 24 is a section taken along the line 24—24 in Fig. 23, looking in the direction of the arrows, or toward the underside of the powder container.

Fig. 25 is a section along the line 25—25 in Fig. 23, looking in the direction of the arrows, and showing the adjustable feature provided on one of the gates for controlling the powder flow through the associated conduit.

Figs. 26 and 27 are views looking at the underside of the powder container, or in the direction of the arrow 26 in Fig. 23, showing the closed and fully opened positions, respectively, of the gates which control the powder flow through the several conduits leading to the brushes.

Fig. 28 is an enlarged end elevation of the machine, as viewed in the direction of the arrow 28 in Fig. 4, showing the squeegee mechanism.

Fig. 29 is a fragmentary, sectional elevation taken along the line 29—29 in Fig. 28, looking in the direction of the arrow, and showing the devices for releasably locking the squeegee in working relation to the floor.

Fig. 30 is a sectional elevation of the dirty water tank, as viewed in the direction of the arrow 30 in Fig. 1.

Fig. 31 is a vertical, sectional elevation of the whistle or signal means that is associated with the dirty water tank for the purpose of notifying the operator when this tank is filled.

Referring to Fig. 1 of the drawings, my im-

proved machine generally comprises a wheeled frame 10 which is partially supported and driven forward by a pair of driving wheels 11. Resting on the frame is a clean water tank 12 which is appropriately connected by a system of piping to a scrubbing mechanism 13 and to this mechanism is also fed a washing compound, generally a soap or cleansing powder, from a distributor 14. Rearwardly of the driving wheels and also supported by the frame 10 is a squeegee mechanism 15 which serves the dual purpose of collecting the dirty water emulsion formed by the scrubbing action, this emulsion being thinned after the scrubbing operation by the addition of clean water from the tank 12, and also serves to wipe the floor clean. The dirty water collected within the confines of the squeegee 15 is evacuated by a device hereinafter described into the dirty water tank 16 and at an appropriate time in the operation of the machine, the operator is warned by a signal means that the tank 16 is filled.

The machine is therefore self-propelled and operates to clean a width of floor equal to the width of the brushes provided on the scrubbing mechanism. Normally, the machine operates along straight lines, but is capable of having its direction of movement readily changed by the operator without interrupting the major functions of the machine. The machine is a self-contained unit in that it not only performs the ordinary scrubbing and wiping operations, but it is also provided with all the facilities necessary for supplying the cleansing materials, as well as evacuating the dirty water.

For the purpose of description, it is convenient to divide the machine into its various structural and operative features and these aspects of the machine will now be described.

Frame and main drive

Referring to Figs. 1 to 5, inclusive, the numeral 17 designates a skeleton frame having the generally rectangular shape shown in plan view in Fig. 5 and which has attached at the forward end thereof a V-shaped extension 18. At the vertex of this extension is suitably mounted a pilot caster roller 19 whose supporting shank is rotatably mounted in the frame extension 18 so that the direction of the machine can be readily changed.

Adjacent the rear end of the frame, a driving axle 20 (see Figs. 5, 6, and 7) is bridged between and journaled in a pair of downwardly extending brackets 21 that are secured to the frame and freely rotatable on the ends of the axle 20 are driving wheels 22.

Referring more particularly to Figs. 10 and 11, the axle 20 extends through each wheel 22 and has fixedly attached to the extremity thereof a hub 23 which is provided with a plurality of radially extending arms 24. A dog 25 is pivotally mounted, as at the point 26, on each of the arms 24 and each dog is provided at its outer extremity with a shoe portion 27 having an arcuate surface that is intended to engage with the inner, peripheral surface of the wheel 22. As clearly indicated in Fig. 10, the wheel 22 is substantially I-shaped in sectional elevation with the web of the wheel disposed substantially midway between the sides thereof. Accordingly, it is possible by this construction to not only provide for the peripheral surface that is frictionally engaged by the dogs 25, but to substantially house these dogs in one side of the wheel.

For a purpose presently explained, the center of curvature of the arcuate surface of the shoe portion 21 is offset from a line connecting the centers of the pivot 26 and of the axle 20 and, for the right-hand driving wheel which is illustrated in Figs. 10 and 11, this offsetting would be to the right of the indicated line. A stub arm 28 projects from one side of the dog 25 and secured to this arm is one end of a coil spring 29 whose opposite end is attached to the arm 24. The tendency of this spring is to force the dog 25 into frictional contact with the wheel 22.

Intermediate the brackets 21 which support the axle 20 is a sprocket 30 which is fast on the axle and operating over this sprocket is a chain 31 which also operates around a sprocket 32 that is secured to a friction drum 33 freely rotatable on a shaft 34 (see Figs. 6 to 9, inclusive). The shaft 34 extends transversely of the principal frame of the machine and at its outer end is journaled in a bracket 35 that also depends downwardly from the frame and is located outwardly of the left-hand bracket 21, as viewed in Fig. 6. The inner end of the shaft 34 is suitably journaled in a gear case 36 that is appropriately hung from the frame and within this case is a worm gear 37 that is secured to the shaft 34. The worm gear 37 meshes with a worm 38 which is drivably connected to the armature (not shown) of the main drive motor 39 that is also appropriately suspended from the frame. The motor 39 is electrically connected by wires (not shown) to a switch box 40 that is supported on a superstructure, generally indicated by the numeral 41 in Fig. 1 and which extends upwardly from and is carried by the principal frame 17. The switch box 40 is provided with a switch 42 for controlling the operation of the motor 39.

The friction drum 33 constitutes one of the principal elements of the clutch for controlling the transmission of power from the motor 39 to the driving axle 20 and positioned within this drum and adapted for frictional driving contact with the inner peripheral surface thereof is a split, springy, friction band 43. One end of this band abuts against a shoulder 44 provided on a pin 45 that is fixedly mounted in a hub 46 that is keyed to the shaft 34, while the opposite end of the band abuts against a similar shoulder 47 provided on a rotatable pin 48 that extends outwardly of the hub 46 (see Fig. 8). A lever arm 49 projects inwardly from the pin 48 in offset relation to the shaft 34, the arm 49 and pin 48 forming a unitary structure, so that when the lever arm 49 is rocked as hereinafter described, the friction band 43 is expanded outwardly into driving contact with the drum 33 against the abutment provided by the shoulder 44 and, when the lever arm 49 is moved to the position indicated in Fig. 9, the normal, retracting action of the band 43 places it in the position shown in the indicated figure, i. e., in a released position.

In order to reduce frictional losses in the operating mechanism, the lever arm 49 is preferably provided with an encircling roller 50 which is engaged by a frusto-conical shifting collar 51 that is freely slideable along the shaft 34. The collar 51 is provided with an annular channel 52 which is embraced by a band 53 having a pair of radially extending trunnions 54. Each of these trunnions is engaged by the forked end of a yoke 55 (see Figs. 6, 7, and 8) and this yoke is pivotally mounted, as by the pins 56 upon a pair of laterally extending ears 57 formed on the bracket 35. As indicated in Figs. 6 and 8, the

shifting collar 51 is in a released position and it is normally held so by means of a coil spring 58, one end of which is connected to an extension 59 formed on the yoke and the other end is connected to the gear case 36.

The yoke 55 is also provided with an arm 59a which extends laterally of the machine beyond the bracket 35 and substantially pivotally connected to this arm is one end of an operating rod 60 whose opposite end extends upwardly along the side of the machine (see Fig. 1) and is substantially pivotally connected to one arm of a lever 61 which is pivotally mounted on the side of a guide rod 62 that extends downwardly and diagonally along the adjacent side of the machine and is bent rearwardly thereof and shaped as a hand grip 63. The other arm of the lever 61 is formed as a trigger grip 64, this trigger grip being located conveniently to the adjacent hand grip 63 so that the operator has at all times immediate control of the main driving clutch.

From the foregoing description, it will be obvious that, when the operator lifts the trigger grip 64 upwardly from the position shown in Fig. 1, the clutch collar 51 will be shifted toward the right, as viewed in Figs. 6 and 8, and will thereby establish a power connection between the motor 39 and the driving axle 20.

As viewed from the right-hand side of the machine, i. e., as illustrated in Fig. 3, the rotation of the driving axle 20 is in a clockwise direction and, due to this direction of rotation and the manner of mounting the dogs 25 on the hub 23, it will be obvious that the shoe portions of the dogs will be thrown into frictional driving contact with the wheels 22, thereby self-propelling the machine. The action is similar to that of a toggle mechanism, the axle and the point where the shoe contacts the wheel forming the ends of the toggle and the dog pivot 26 acting as the knee of the toggle.

This driving connection with the wheel 22 will be maintained so long as the machine moves along a straight line. If the operator wishes to change the direction of the machine, it is merely necessary to point the machine in the desired direction, whereupon the rotation of the then outside driving wheel relative to the rotation of the driving axle will automatically effect a release of the driving dogs 25.

The indicated change in direction of the machine, however, only automatically interrupts the flow of power to the then outside wheel, power connection being maintained with the inside wheel so that the machine is still self-propelled while making the change in direction.

As additional features of the frame construction, and as indicated in Fig. 5, the frame 17 may be provided with guard rails 66 which are located forwardly of the driving wheels and the distance between which, transversely of the machine, is greater than the over-all tread of the wheels. These guard rails may be provided with a protective strip of rubber 67 and each rail is also provided with a freely rotatable guard wheel 68. Accordingly, the machine may be operated relatively close to walls and baseboards without injury to the latter.

Scrubbing mechanism

Referring to Figs. 12 to 15, inclusive, the scrubbing mechanism hereinbefore referred to by the numeral 13, generally comprises a pair of individually mounted and driven brushes which are pivotally mounted on the frame so that each

brush applies a substantially constant scrubbing pressure to the floor, as well as accommodating itself to any irregularities that may be encountered on the floor surface. The brushes are further arranged so that the areas contacted thereby overlap, thus avoiding any possibility of the machine leaving a streaked line between the individual brushes.

Referring more particularly to Fig. 14, a pair of spaced arms 70—70 depend downwardly from the forward cross member 69 of the frame and pivotally mounted on the lower ends of these arms are the ends of the limbs of a U-shaped cradle 71 which extends forwardly of the machine and is located on the right side of the machine, as viewed in Fig. 12. On the left side of the machine, a pair of downwardly and forwardly projecting arms 72 extend from the cross member 69 and pivotally mounted on the lower ends of these arms are the ends of the limbs of a similarly U-shaped cradle 73.

A motor 74 is mounted on the cradle 73 and is electrically connected by wires (not shown) to a switch designated by the numeral 75 in Fig. 2. Forwardly of the motor 74, the cradle 73 also supports a gear case 76 in which is suitably journaled a worm 77 that is connected to the armature (not shown) of the motor 74. The worm 77 meshes with a worm gear 78 that is fast on a shaft 79 which extends downwardly through the bottom of the case 76 and has its lower end secured to one-half of a universal coupling 80. The lower half of this coupling is formed as an elongated, flat plate 81 and extends through a correspondingly shaped aperture provided in the hub 82 of a brush ring denoted generally by the numeral 83 (see Fig. 15).

A T-shaped slot 84 extends in and upwardly from the lower face of the plate 81 and the limbs of this T form hook-shaped recesses for receiving the prongs of a U-shaped spring clip 85 whose arms normally diverge and are pressed towards each other by the downward insertion of the plate 81 through the medium of inclined faces 86 provided on the upright of the T-shaped slot. By virtue of this construction, the brush ring 83 and hence the brushes may easily accommodate themselves to surface irregularities in the floor, vertical irregularities being accommodated by the principal pivotal mounting of the cradle 73, while other irregularities are accommodated by the loose and universal mounting of the brush.

The brush ring hub 82 is connected by a plurality of radial arms to an annular vertical wall 87 from which projects outwardly a flat, annular flange 88 provided around its periphery with a downwardly extending lip 89. A plurality of segmental-shaped brushes 90 are seated against the inside, upper surface of the flange 88 and against the annular lip 89 and are held in this position by means of a plurality of bowed springs 91, each of which bear at their ends against the backing 92 of the associated brush and at their middle portions against the annular wall 87. In order to maintain the brushes in the indicated position when the brush rings are lifted, as hereinafter described, the annular lip 89 may be tapered slightly inwardly with a corresponding formation provided on the adjacent portion of the brush backing.

Similarly, the cradle 71 supports a motor 83 which is connected by wires (not shown) with an operating switch 94 provided in the switch box 40 (see Fig. 2). The remaining construction of this particular portion of the machine is iden-

tical with that heretofore described and it will be understood that the brushes 95 are mounted in the associated brush ring and connected to the motor 93 in the same manner as are the brushes 90 to the motor 73.

Due to the forward disposition of the cradle supporting arm 72, it is clear from an examination of Fig. 14 that the brushes 90 will lie slightly forwardly of the brushes 95 when in operative relation to the floor. By this construction, it is possible to so position the brushes 90 and 95, transversely of the machine as to provide for a slight overlap of the floor areas contacted by each brush. This arrangement is an important feature of my machine, as it is thereby possible to provide the machine with a plurality of brushes which manifestly increases the cleaning or scrubbing rate of the machine without any danger of leaving streak lines between the adjacent edges of the brushes. A further very important feature of the machine resides in the pivotal mounting of the cradles which are employed to support each brush and the individual motor drive to each brush. By adopting this construction, it is possible to make the machine substantially independent of any discrepancies in the floor surface as would otherwise occur in a multi-brush machine, or in a single brush machine, where the brushes are more or less rigidly attached to the machine frame. The motor, gear cases, and associated parts provide sufficient weight to insure an adequate scrubbing pressure of the brushes.

When the machine is not in use, or when it is desired to move the machine from place to place without scrubbing, it is desirable that the brushes be elevated from the floor. For this purpose, an arm 96 is fastened to and projects laterally from the gear case 76 and projecting downwardly through an aperture in this arm is a link 97 which carries at its lower end below the arm 96 a pair of lock and adjusting nuts, designated generally by the numeral 98. Above the arm 96, the link 97 is bent and rotatably mounted in the lower end of a rock arm 99 whose upper end is fast to a cross operating shaft 100 that is journaled in the frame extension 18 (see Fig. 5). A similar linkage 101 is connected to the right-hand scrubbing machine, as viewed in Fig. 12.

The operating shaft 100 extends beyond the frame of the machine on the left side thereof and has attached thereto a rock arm 102. One end of an operating rod 103 is connected to the arm 102 and this rod extends upwardly and rearwardly for pivotal connection to a manual brush lever 104 which is pivotally mounted on the superstructure 41 adjacent the rear end of the machine. When the lever 104 is moved from the position indicated in Fig. 1 rearwardly to a position in which the pivotal connection of the rod 103 to the lever 104 passes beyond the pivot of the lever, it is obvious that the mechanisms just described will lift both sets of brushes from the floor and will hold them in the lifted position. The nuts 98 and their counterpart on the link assembly 101 are positioned so that, when the lever 104 occupies the position illustrated in Fig. 1, the brushes will exert full scrubbing contact with the floor.

70 Water distribution

One of the important features of my improved machine is the manner in which the flow rate of water to each brush is controlled so as to insure that each brush will receive an equal quan-

ity of water. This control is important, in conjunction with a similar control on the flow of cleansing powder to the brushes, because otherwise there could not be any assurance that the brushes were receiving equal quantities of cleansing material. Failure to insure this mode of operation frequently results in a starving of one brush and an excess delivery of cleansing material to the other brush. Obviously, such an arrangement not only results in an uneconomical use of the cleansing material, but also an improper cleansing of the floor due to the unevenness of distribution and therefore an inequality in the emulsion strength of the cleansing liquid as between the two brushes.

Referring to Figs. 5 and 16 to 20, inclusive, the clean water tank 12 is connected by means of a supply pipe 105 with a T-fitting 106. One branch of this fitting connects by means of a hose 107 with a valve body 108 within which is rockably mounted a valve plug 109 for controlling the water flow therethrough. Outwardly of the valve body 108, the plug 109 has secured thereto an arm 110 through which is threaded one end of a right- and left-hand threaded stem 111, the opposite end of this stem being threaded through the free end of an arm 112 whose opposite end is fixedly attached to one end of a rock shaft 113. The stem 111 may be adjusted to secure any desired space relation of the arms 110 and 112 and this adjustment may be maintained by means of a lock nut 114.

The rock shaft 113 extends transversely of the machine and is suitably journaled in the frame. At the opposite side of the machine, the shaft 35 113 is secured to a rotary valve plug 115 which operates in a valve body 116. The valve body 116 is connected by a hose 116a to the fitting 106. Hoses 117 and 118 connect the valve bodies 108 and 116 with funnels 119 and 120 for delivering water to the inside of the brushes 95 and 90, all respectively.

Also fixedly attached to the valve plug 109 is an arm 121 which is pivotally connected to the lower end of an operating rod 122 (see Figs. 1 and 17) which extends diagonally upwardly and rearwardly of the machine for pivotal connection to an operating handle 123 (see Figs. 19 and 20) which is pivotally mounted on a pin 124 that is secured in a dial plate 125 mounted on the 45 plate and is bent over into proximity to an annular flange 130 provided on the dial plate 125. A release pin 131 is reciprocably mounted in a boss 132 provided on the handle 123 and the inner end 133 thereof is spring pressed into contact with the peripheral surface of the flange 130.

By the foregoing arrangement, it is possible to position the disk 128 and hence the stop tongue 129 so as to limit the movement of the operating handle 123 from the fully closed position illustrated in Fig. 19 to some position short of the fully opened positions of the valves 108 and 116. At the same time, the provision of the release pin 131 renders it possible to move the 50

indicated valves to a fully opened position merely by withdrawing the release pin 131 sufficiently to clear the stop tongue 129.

In the operation of the machine, and as noted 5 above, when the operating handle 123 occupies the position shown in Fig. 19, water is prevented from flowing to the brushes, but when moved forwardly from the indicated position, water will flow to each brush dependent upon the extent of 10 movement of the handle 123 and, also, by reason of the adjustment provided by the threaded stem 111, it is possible to insure that the flow rate of water to each brush is the same. This result is due to the fact that, for any desired angular 15 movement of the valve plug 109, it is possible to so adjust the threaded stem 111 that substantially the same extent of angular movement is imparted to the rock shaft 113 when the operating rod 122 is moved. When this adjusting mechanism is once set, it operates to equalize the flow rate to the respective brushes between the limiting positions of the operating handle 123.

Also associated with my improved water distribution system is an arrangement of piping 25 for delivering rinsing water to the floor immediately to the rear of the scrubbing brushes in order to further liquefy the dirty water emulsion in order to facilitate its subsequent removal, as well as to further loosen the dirt from the floor.

To this end, one end of a pipe 134 is connected to the T-fitting 106 (see Fig. 16) and the opposite end is connected to a valve 135. A valve plug 136 is rockably mounted in the valve 135 and has fastened to its exposed end a rock arm 137 which is joined by an intermediate lever-link connection, denoted generally by the numeral 137a in Fig. 13, to an operating rod 138 that extends diagonally upwardly and rearwardly along the right side of the machine, or as viewed in Fig. 3, for pivotal connection to the free end of a rock arm 139 that is pivoted on a guide bar 140. The bar 140 is similar in construction and similarly located relative to the remainder of the machine as is the bar 62. Integrally formed with the rock arm 139 is a trigger release 141 which is located conveniently close to the hand grip 142 provided on the guide bar 140. Accordingly, as the operator guides the forward movement of the machine by gripping the handles 63 and 142, he also has ready for immediate control by his left hand the trigger release 144 for controlling the forward motion of the machine and also the trigger release 141 for regulating the flow of rinsing water to the floor. The valve 135 is so constructed that an upward movement of the trigger release 141 from the position shown in Fig. 3 operates to cause a flow of water through the pipes 134 and 143 to the floor.

60 Cleaning compound distributor

The cleaning compound ordinarily employed in machines of this type is of a powdery nature and in order to maintain this powder in a fluffy and well mixed condition, thus avoiding any possibility of the heavier portions thereof separating and dropping to the bottom of the storage container, it is customary to provide such machines with agitating means to insure this end. 65 Similar provision is made in my improved machine.

Referring, therefore, to Figs. 1 and 21 to 27, inclusive, the powder distributor comprises a storage container 143 which is generally elongated in plan view and generally trough shaped 70

in sectional profile, as clearly indicated in Fig. 22. The container is supported on an adjustable frame extension 144 which projects forwardly from the superstructure 41 (see Fig. 1) so as to position the container 143 substantially immediately above the scrubbing brushes.

The lower, inner wall surface of the container is rounded, as indicated by the numeral 145 in Fig. 22, and an agitator shaft 146 extends across the length of the container and projects through the walls thereof for journal support in the extension 144. A pair of agitators 147 are fixed to the shaft 146 adjacent the ends of the shaft (see Fig. 23) and each of these agitators is formed with a plurality of radially extending fingers 148, each of which terminates in curved flanges 149 which are disposed parallel to the shaft 146. These flanges operate relatively close to the curved bottom 145 of the container and, by their rotation, the powder is sufficiently agitated to prevent any separation of the component elements as well as breaking up any lumps in the powder and preventing caking or bridging.

The agitator shaft 146 projects beyond the left end of the container 143, as viewed in Fig. 23, and has keyed thereto a pinion 150 which is provided on its outer face with a plurality of circumferentially spaced lugs 151 which are utilized for a driving engagement with the parts hereinafter described. The pinion 150 meshes with a gear 152 that is secured to a shaft 153 located below and in the same vertical plane with the shaft 146. The shaft 153 is journaled in spaced lugs 153^a depending from the bottom of the container 143 at the ends thereof and has secured thereto star wheels 154 and 155 which respectively operate in downwardly extending passages 156 and 157 formed in the lugs 153^a. The position of the shaft 153 is such that the peripheral points of each of the star wheels project above the curved bottom of the container during the operation of the shaft and each star wheel is in substantially vertical alignment, transversely of the container 143, with the adjacent agitator 147.

As noted above, the agitators 147 maintained the powder in the container in a thoroughly mixed and fluffy condition so as to insure a free flow of the powder downwardly through the passages 156 and 157. Similarly, the star wheels perform the same function with reference to the powder passing through their respective passages and at the same time, due to their conformation, exert a slight feeding or pushing movement on the powder which inhibits any tendency toward clogging in the passages.

A thin, flat plate 158 is fastened to the undersides of the lugs 153^a and is provided with apertures 159 and 160 which register with and have substantially the same area as the passages 156 and 157, respectively, these apertures forming the supply outlets from the powder container. It will be noted from Figs. 22, 23 and 24 that each star wheel fits snugly across the width of the associated passages and that its diameter is only slightly less than the length of the passage measured at a cross-section. This fact, coupled with the pockets formed around each wheel by the radial wings and the projection of each wing above the bottom of the powder container when in the position illustrated in Fig. 22, insures the collection and delivery of a succession of powder charges which are substantially measured by the pockets.

One of the most important features of my improved machine resides in the control on the

flow rate of the powder, this control being so exercised as to insure a correct proportioning of the powder to the water supplied to the several brushes so as to obtain a cleaning emulsion of proper strength, and the powder control is also arranged so as to insure that equal amounts of powder will be supplied to each brush. The instrumentalities for achieving these ends will now be described.

10 A flat plate constituting a control gate 161 is pivotally mounted on a pin 162 carried by the plate 158, the pin 162 being located to the right of the aperture 159 and the width of the plate being such as to entirely mask the aperture 159 when the plate occupies the position shown in Fig. 24, but when pivoted on the pin 162 the rate of flow through the aperture 159 will depend upon the then position of the gate 161.

To the right of the pin 162, the gate 161 is 20 reduced to form a parti-circular nose 163 which operates in a similarly shaped recess 164 provided on a flat plate 165 that is also pivoted on a pin 166 carried by the plate 158.

The plate 165 acts as a gate to control the 25 movement of powder through the aperture 160, but this gate is modified, relative to the gate 161, to include an adjustment that is constructed and arranged to insure that, for any angular movement of the gate 161 which results in an 30 unmasking of the outlet 159 to any extent, the same degree of unmasking will be achieved with respect to the outlet 160. This construction, therefore, compensates for any discrepancies in the fitting of the parts, such as might occur 35 during manufacture and assembly, or that might subsequently occur by reason of wear. In this connection, it will be understood that the distance from the pin 162 to the center of the outlet 159 is exactly equal to the distance from the pin 166 to the center of the outlet 160, and, since the gate plates 161 and 165 are interconnected at a point midway between the pins 162 and 166, any angular movement imparted to the gate 161 will effect an angular movement of the same extent of the gate plate 165.

The gate plate 165 terminates short of the supply outlet 160 and its top and bottom surfaces are embraced by a pair of spaced, top and bottom plates 167 and 168 which are brought into 50 touching relation to form the gate member 169 that extends beyond and in masking relation to the outlet aperture 160. The bottom plate 168 is slit transversely in two spaced locations, as indicated by the numeral 170, and the portion between the slits is then bent downwardly to 55 form a flange 171 which is slotted upwardly from the bottom edge thereof as indicated by the numeral 172 (see Fig. 23). The reduced, threaded stem 173 of an adjusting screw 174 is rotatably mounted in the slot 172 and is also threaded through a stud pin 175 that is fixedly mounted in the gate plate 165. The flange 171 is gripped 60 between a nut 176 that is mounted on the reduced portion 173 and the enlarged hand grip portion 174 of the adjusting screw. Accordingly, since the adjusting screw 174 cannot move relatively to the gate member 169, when the screw is rotated, it will move the gate member 169 transversely and relative to the gate plate 165. By this adjustment, the gate member 169 can 65 be placed in a leading or retarded position relative to the pivoting of the gate plate 165 and, hence, for any given unmasking of the outlet 159 by the gate 161, it is possible to secure the same degree of unmasking of the outlet 160.

Integrally formed with the gate 161 and extending beyond the left end of the powder container, as viewed in Fig. 23, is a cam plate 177 that is provided with an L-shaped cam slot 178 composed of a slot portion 179 that is slightly angularly inclined to the gate 161 when the latter is occupying the closed position illustrated in Fig. 26, while the other slot portion 180 occupies an almost normal position with reference to the same plate in the same position. A cam roller 181 operates in the slot 178 and the roller is carried by the curved, lower end of a U-shaped yoke 182, whose limbs extend upwardly and are pivotally mounted on the frame extension 144. The upper end of each yoke limb is provided with a roller 193 that operates in an annular channel on a collar 184 that is freely rotatable on and shiftable endwise relative to the shaft 146. The collar 184 is positioned in operating relation to the pinion 150 and the inner face of the collar is provided with a plurality of circumferentially spaced lugs 185 which are intended to engage with the lugs 151 in order to establish a driving connection with the pinion 150.

A sprocket 186 is integrally formed with or otherwise connected to the collar 184 so as to partake of all movements of the latter and a chain 187 (see Fig. 3) operates over this sprocket, a pair of idler sprockets 188 suitably mounted on the machine frame, and has driving connection with a sprocket 189 (see Figs. 5 and 10) that is secured to the right-hand driving wheel 22.

The gate 161, and accordingly the cam plate 177, is pivoted by means of an operating link 190, one end of which is pivotally connected to the cam plate and the other to one end of a lever 191 that is pivoted on the frame extension 144. The opposite end of the lever is pivotally connected to the lower end of an operating rod 192 that extends rearwardly and diagonally upward for connection with a hand control mechanism, generally indicated by the numeral 193, and whose construction is identical with that heretofore described for the water distribution system and illustrated in Figs. 19 and 20. As with the water control, this powder control mechanism incorporates a hand lever 194 which may be moved from the fully closed position illustrated in Fig. 3 to a fully opened position, or to any position short of the fully opened position, by engagement with a stop 195 corresponding to the stop 129 in Fig. 19.

In the operation of the machine, it will be obvious that, when the machine is moving forward, the sprocket 186 and the collar 184 will be idling loosely on the agitator shaft 146 by virtue of the connection of the two first noted parts with one of the driving wheels. Further, it will be assumed that the gate member 169 has been adjusted to insure an equal rate of flow through the outlets 159 and 160 and, also, that the stop 195 on the hand control mechanism 193 has been positioned to limit the opening movement of the operating handle 194 to the extent required to obtain the correct mixture with the water supplied to the brushes.

Hence, when the operator moves the handle 194 forwardly from the position illustrated in Fig. 3, the ensuing movement of the cam plate 177 moves the roller 181 along the slot portion 179. Because of the angular position of this slot portion, there is thus effected a rapid endwise movement of the collar 184 toward the right so as to engage the

lugs 151 and 185 and so establish a driving connection with the agitator shaft 146 and the star wheel shaft 153. The indicated traverse of the roller 181 in the slot portion 179 also effects a partial unmasking of the outlets 159 and 160, but, after the driving lugs 185 and 151 have been fully engaged, further endwise movement of the collar 184 is unnecessary. At this time, then, the cam roller 181 begins moving through the slot portion 180, i. e., in a direction generally transverse to the axis of the shaft 146. Accordingly, the cam plate 177 may be further moved up to the limit established by the stop 195 without affecting the then driving position of the collar 184.

Powder delivered through the outlets 159 and 160 passes into flexible tubes 196 and 197, respectively, and the lower ends of these tubes discharge into the funnels 120 and 119, respectively, (see Fig. 12) and thus into the space within each brush annulus. It will be particularly noted, from an examination of Fig. 12, that the powder is discharged into the indicated funnels above the point of entrance of the water through the pipes 118 and 117. Hence, this relation of the indicated parts not only insures a thorough premixing of the powder and water before being delivered to the brushes, but also insures that the water will prevent any tendency toward clogging of the funnels by the downwardly moving powder.

Squeegee mechanism

The purpose of the squeegee mechanism is to wipe the floor clean after the scrubbing operation and also to collect the dirty water left by the brushes within the partial enclosure defined by the squeegee proper so that it may be evacuated into the dirty water tank carried by the machine.

Referring to Figs. 4, 5, 28 and 29, the numeral 198 designates a U-shaped treadle whose limbs are pivotally mounted upon the downwardly extending brackets 21 and whose closed end extends rearwardly of the machine for convenient access by the foot of the operator. A V-shaped squeegee member 199 is pivotally mounted on the limbs of the treadle 198 rearwardly of the driving wheels 22 and the wiping width of the squeegee is greater than the tread of the wheels. Oppositely acting adjusting screws 200 (see Fig. 5) may be employed to correctly limit the rocking movement of the squeegee. When the machine is not in operation, the squeegee is elevated from the floor contacting position illustrated in Fig. 4 by means of a pair of coil springs 201 whose lower ends are connected to the treadle 198 and whose upper ends are fastened to the machine frame.

The squeegee proper is composed of a flexible strip 202, which may be formed of rubber or other suitable material and backing this strip preferably is a second strip 203 of like material whose width, however, is less than that of the wiping strip 202. The two flexible strips are fastened to a metallic frame 204 which in turn is pivotally mounted on the treadle 198.

Within the confines of the treadle 198 a swingable lever 205 depends from the machine frame and it is provided with an adjustable catch block 206 that is intended to be engaged by a cross bar 207 mounted across the limbs of the treadle 198. Integrally formed with the swinging lever 205 is a trigger release pedal 208 that extends slightly rearwardly and upwardly for convenient access by the operator. The arm 205 is normally biased to insure the engagement of the cross bar 207 with the catch block 206 by means of a coil spring

209 which is connected at its ends to the release pedal 208 and to the operating treadle 198.

One end of a coil spring 210 is also connected to the cross bar 207 and the opposite end of the spring is fastened to a switch 211 (see Fig. 28) which controls the operation of a motor 212 (see Fig. 1). The motor 212 is drivably connected to a vacuum pump 213 whose inlet 214 is in communication with the upper portion of the dirty water tank 16 and whose discharge is effected through a downwardly extending hose 215. The outlet of this hose is located forwardly of the squeegee and hence in a position that will not mar the cleaned floor rearwardly of the squeegee. A water suction hose 216 extends downwardly from the bottom of the dirty water tank 16 into close proximity to the floor and immediately forwardly of the vertex of the squeegee.

Associated with the dirty water tank is a device for warning the operator when the dirty water tank is filled. This device takes the form of a float 217 located within the tank 16 and provided with a stem 218 which extends vertically upward and is guided through a rod 219. The stem extends outwardly through the top of the tank and is connected to a valve 220 which engages with a valve seat 221 in a casing 222 mounted on the tank top. Carried by the top of the casing 222 is a whistle device 223 having a top plate 224 whose central portion is formed by a pair of spaced and suitably curved elements 225, each of which is provided with an aperture 226. This construction, therefore, approximates the ordinary air whistle device.

In the operation of the squeegee mechanism, it will be understood that the wiping strip 202 is only moved into operative relation to the floor when the machine is performing its usual function of scrubbing, etc. At all other times the squeegee is maintained in an elevated position by means of the springs 201.

When the machine is operating, however, the treadle 198 is depressed against the action of the springs 201 until the cross bar 207 engages with the catch block 206, thus moving the squeegee into contact with the floor and maintaining this wiping contact by means of the engagement between the block 206 and the cross bar 207.

During the movement of the squeegee to working position, the switch 211 is shifted to complete the circuit through the motor 212, so that the vacuum pump 213 is thereby placed in operation to establish the required vacuum in the dirty water tank 16. Accordingly, as the machine is moved along the floor, the dirty water collected by the wiping strip 202 is drawn through the suction pipe 216 into the tank 16, and the strip 202 thereafter wipes the floor clean. As noted above, the squeegee is located rearwardly of the driving wheels, thus eliminating any possibility of the floor being marred or streaked by the machine. Moreover, the partial enclosure formed by the squeegee is sufficiently large to insure, in conjunction with the floor speed of the machine and the removal rate of the dirty water, that none of the latter will escape beyond the extremities of the squeegee.

The establishment of a partial vacuum in the dirty water tank assists in maintaining the air relief valve 220 in a closed position and this action it facilitated, by the weight of the associated parts of the float. As the water rises in the tank 16, it eventually reaches a level at which further upward movement of the water effects a lifting of the float 217 and, hence, an opening

of the valve 220. Air rushing from the outside through the whistle device 223 sets up a shrill sound which warns the operator that the tank 16 must be emptied.

5 The emptying operation is effected by lifting a valve 227 which opens the outlet to a discharge pipe 228. The valve 227 is normally held in a closed position by means of a coil spring 229 which encircles the valve stem and bears against 10 an appropriate shoulder formed thereon and against an arm 230 provided in the tank. The stem of the valve extends upwardly through the top of the tank and is provided with a hand grip portion 231. The tank 16 may also be provided 15 with a hand hold cover 232 which provides convenient access to the interior tank for purpose of cleaning.

Auxiliary features

20 Since certain of the mechanisms of the machine are electrically operated, it is necessary to provide a means for supplying current to the several motors and to so arrange this means that it will impart to the machine a wide radius of action.

25 To this end, a reel 233 is mounted on the superstructure of the machine and wound around this reel is an electrical cable 234 having any desired length and which operates over a pair of trolley 30 wheels 235 that are mounted on a swivel connection 236. The plug end 237 of the cable may be inserted in any convenient electric socket and it will be understood that the opposite end of the cable is connected by suitable wires to the several 35 motors and switches hereinbefore described.

Conclusion

The machine as above described provides a self-contained unit for thoroughly scrubbing and 40 wiping strips of floor having a width equal to the operative width of the machine by a single movement of the machine along the floor. Repeated traverses of the same strip by the same or different types of machines are thereby eliminated with a corresponding saving in cleaning 45 time. The radius of action of the machine is limited only by the amount of electrical cable which may be conveniently handled therewith and, at all times, during the operation of the 50 machine the various mechanisms thereof are under the instantaneous control of the operator, since the control features of these mechanisms are located conveniently to the guiding handles which the operator normally holds. The machine is economical in its use of cleansing materials, including the water and the powder, because of the adjustable features which render it possible to secure the desired mixture of these 55 materials, and also the delivery of equal quantities of these materials, respectively, to the brushes.

In the preferred use of the machine, power is applied to each of the brushes before they are lowered into contact with the floor, or if already 60 in floor contact but at rest, the brushes are lifted for this purpose. The brushes are, therefore, rotating at speed when they contact the floor, and since they are started under light load conditions, the starting load on the motors is relatively light, thus lessening wear on the motors and reducing the possibility of blowing fuses in the circuit providing the electric current.

The delivery of the cleaning materials to the interior of the brushes, that is, to the spaces within the brush rings proper, insures a proper

distribution by the centrifugal action of the brushes as the machine moves forward. This characteristic operation of the machine in conjunction with the individual mounting and overlapping relation of the brushes and the equalized delivery of cleansing material to the brushes eliminates any possibility of the machine leaving light and dark spots or streaks on the floor.

The normal lineal speed of the machine is 135 feet per minute and this speed can be raised or lowered as desired by changes in the gearing. At the speed stated, the machine has a cleaning capacity of approximately 10,000 sq. ft. per hour.

It is contemplated that the individual and universal mountings of the brushes can also be applied to floor polishing machines and, hence, where the term "floor treating device" is used in the claims, it is intended to include within the scope of this term scrubbers as well as polishers.

I claim:

1. In a floor scrubbing machine, the combination of a scrubber, a funnel for conveying the scrubbing material to the scrubber, and separate pipes for delivering water and cleaning powder to the funnel, the ends of the pipes being closely adjacent to each other to thereby secure a preliminary mixing of the water and powder and prevent any tendency of the powder to choke in the funnel.

2. In a floor scrubbing machine, the combination of a wheeled frame, a scrubber mounted on the frame, means for feeding cleaning compound to the scrubber, and means for simultaneously delivering water to the scrubber for mixing with the compound to make a scrubbing emulsion and to the floor immediately to the rear of the scrubber to thin the dirty water preliminary to removal.

3. A cleaning powder distributor for a floor scrubbing machine provided with a pair of scrubbers comprising in combination, a powder container, a delivery conduit leading from the container to each scrubber, a gate for each conduit, one of the gates being adjustable relative to its conduit to provide for a rate of flow therethrough substantially equal to the rate of flow through the other conduit, and means for simultaneously operating both gates.

4. A cleaning powder distributor for a floor scrubbing machine provided with a pair of scrubbers comprising in combination, a powder container, a delivery conduit leading from the container to each scrubber, a pivoted gate for each conduit, the gates being interconnected midway between their pivots for simultaneous movement through equal angles, and means for operating the gates, one of the gates having a part adjustable relative to the associated conduit for establishing a rate of flow therethrough substantially equal to the flow rate through the other conduit.

5. A cleaning powder distributor for a floor scrubbing machine provided with a pair of scrubbers comprising in combination, a powder container, a delivery conduit leading from the container to each scrubber, a gate for each conduit, said gates being connected for simultaneous movement through equal angles, and means for operating one of the gates to thereby simultaneously control the flow through both conduits.

6. A cleaning powder distributor for a floor scrubbing machine provided with a pair of scrubbers comprising in combination, a powder container, a delivery conduit leading from the container to each scrubber, separate agitators in

the container and conduits, respectively, for maintaining the powder in a loose and fluffy condition, the conduit agitators additionally feeding the powder through the conduits, driving means clutch connected to the agitators, a gate for each conduit, and control means adapted to preliminarily connect the driving means to the agitators and thereafter simultaneously position both gates to control the powder flow through both conduits.

7. In a floor scrubbing machine, the combination of a frame, a squeegee mounted on the frame and movable between positions clear of and in wiping contact with the floor, a dirty water tank mounted on the frame, a vacuum pump having means for raising and for discharging into the tank the dirty water collected by the squeegee, a motor for operating the pump, and connections between the squeegee and motor for starting the motor when the squeegee is moved to wiping position.

8. In a floor scrubbing machine, the combination of a plurality of scrubbers, a conduit connecting each scrubber with a supply of cleansing material, a valve in each conduit, the valves being relatively adjustable to equalize the flow of material to the scrubbers, and means for simultaneously operating all valves.

9. In a floor scrubbing machine, the combination of a plurality of scrubbers, first and second groups of conduits connecting each scrubber with a supply of water and cleaning compound, respectively, a valve in each first conduit, a valve in each second conduit, the valves in the first conduits being relatively adjustable to equalize the flow of water to each scrubber, and the valves in the second conduits being relatively adjustable to equalize the flow of compound to each scrubber, adjustable means for simultaneously operating the first conduit valves, and other adjustable means for simultaneously operating the second conduit valves whereby the water-compound ratio for each scrubber can be varied.

10. In a floor scrubbing machine, the combination of a pair of scrubbers, a conduit connecting each scrubber with a supply of cleansing material, a valve in each conduit, turnbuckle means connecting the valves whereby the valves may be relatively adjusted to equalize the flow of material to each scrubber, and means for simultaneously operating both valves.

11. In a floor scrubbing machine, the combination of a scrubber, a funnel for conveying the scrubbing material to the scrubber, and separate pipes for delivering water and cleaning powder to the funnel, the delivery end of the water pipe being positioned closely adjacent to and at a lower elevation than the delivery end of the powder pipe to thereby secure a preliminary mixing of the water and powder and prevent any tendency of the powder to choke in the funnel.

12. In a floor scrubbing machine, the combination of a wheeled frame, a plurality of scrubbers mounted on the frame and adapted to accommodate their scrubbing positions to floor surface irregularities as the machine is moved over the floor, a conduit connecting each scrubber with a supply of cleansing material, a valve in each conduit, the valves being relatively adjustable to equalize the flow of material to each scrubber, and means for simultaneously operating all valves.

13. A cleaning powder distributor for a floor

scrubbing machine provided with a pair of scrubbers comprising in combination, a powder container, a delivery conduit leading from the container to each scrubber, a gate for each conduit, one of the gates having a flow controlling member adjustable thereon to provide for a rate of flow through the associated conduit substantially equal to the rate of flow through the other conduit, and means for simultaneously operating both gates.

14. A cleaning powder distributor for a floor scrubbing machine provided with a pair of scrubbers comprising in combination, a powder container, a delivery conduit leading from the container to each scrubber, a gate for one conduit, a second gate for the other conduit comprising a plate, a pin mounted on the plate, a flow controlling plate shiftable on the first-named plate, and an adjusting screw threaded in the pin and engageable with the flow controlling plate to provide for a rate of flow through the associated conduit substantially equal to the rate of flow through the other conduit, and means for simultaneously operated both gates.

15. A cleaning powder distributor for a floor scrubbing machine provided with a pair of scrubbers comprising in combination, a powder container, a delivery conduit leading from the container to each scrubber, an agitator in the container for maintaining the powder in a loose and fluffy condition, driving means clutch connected to the agitator, a gate for each conduit, and control means adapted to preliminarily connect the driving means to the agitator, and thereafter simultaneously position both gates to control the powder flow through both conduits.

16. A cleaning powder distributor for a floor scrubbing machine provided with a pair of scrubbers comprising in combination, a powder container, a delivery conduit leading from the container to each scrubber, an agitator in the container for maintaining the powder in a loose and fluffy condition, driving means for the agitator, a clutch interposed between the driving means and the agitator, a pivoted gate for each conduit, the gates being interconnected midway between their pivots for simultaneous movement through equal angles, one of the gates including first and second cam surfaces inclined and transverse, respectively, to the axis of the clutch, a cam roller guided by the surfaces and connected to the clutch for actuating the same, the cam roller contacting the first surface when the gates are closed, and means for actuating the cammed gate to thereby cause the cam roller to successively traverse the first and second cam surfaces, the latter being arranged and adapted to effect a preliminary connection of the driving means to the agitator and thereafter a simultaneous positioning of both gates to control the powder flow through both conduits.

17. A cleaning powder distributor for a floor scrubbing machine provided with a pair of scrubbers comprising in combination, a powder container, a delivery conduit leading from the container to each scrubber, a first pivoted gate for regulating the flow through one conduit, a second pivoted gate operably connected to the first gate for regulating the flow through the other conduit, and means for rocking the first gate to thereby simultaneously control the flow through both conduits.

18. A cleaning powder distributor for a floor scrubbing machine provided with a pair of scrub-

bers comprising in combination, a powder container, a delivery conduit leading from the container to each scrubber, a pivoted gate for each conduit, the gates being interconnected midway between their pivots for simultaneous movement through equal angles, and means for operating one of the gates to thereby simultaneously control the flow through both conduits.

19. A cleaning powder distributor for a floor scrubbing machine comprising in combination, a powder container, a delivery conduit leading from the container to the scrubbing device, an agitator in the container for maintaining the powder in a loose and fluffy condition, driving means clutch connected to the agitator, a gate for the conduit, and control means adapted to preliminarily connect the driving means to the agitator and thereafter position the gate to control the powder flow through the conduit.

20. In a floor scrubbing machine, the combination of a plurality of scrubbers, a conduit connecting each scrubber with a supply of cleansing material, and a valve for controlling the flow of material through each conduit, the valves being connected for simultaneous movements of equal amplitude to control the flow to all scrubbers.

21. In a floor scrubbing machine, the combination of a wheeled frame, a plurality of scrubbers mounted on the frame and adapted to accommodate their scrubbing positions to floor surface irregularities as the machine is moved over the floor, a supply of cleansing material, and a valve for controlling the flow of material to each scrubber, the valves being connected for simultaneous movement of equal amplitude to control the flow to all scrubbers.

22. A cleaning powder distributor for a floor scrubbing machine having a scrubbing device comprising in combination, a powder container, a delivery conduit leading from the container to the device, an agitator in the container for maintaining the powder in a loose and fluffy condition, driving means for the agitator, a clutch interposed between the driving means and the agitator, a pivoted gate for controlling the powder flow through the conduit and having first and second surfaces inclined and transverse, respectively, to the axis of the clutch, a cam guided by the surfaces and connected to the clutch for actuating the same, the cam contacting the first surface when the gate is closed, and means for actuating the gate to thereby cause the cam to successively traverse the first and second cam surfaces, the latter being arranged and adapted to effect a preliminary connection of the driving means to the agitator and thereafter a positioning of the gate to control the powder flow through the conduit.

23. In a floor scrubbing machine, the combination of a plurality of scrubbers, first and second groups of conduits connecting each scrubber with a supply of water and cleaning compound, respectively, a valve in each first conduit, a valve in each second conduit, the first conduit valves being connected for simultaneous movements of equal amplitude to control the flow of water to each scrubber and the valves in the second conduits being connected for simultaneous movements of equal amplitude to control the flow of compound to each scrubber, whereby the water-compound ratio for each scrubber is the same and may be varied at will.

WALTER S. FINNELL.
